UNITED STATES PATENT OFFICE.

ERNEST LESCHHORN, OF CHICAGO, ILLINOIS, ASSIGNOR TO LATHAM MACHINERY COMPANY, A CORPORATION OF ILLINOIS.

STITCHING MACHINE.

Application filed October 18, 1923. Serial No. 669,240.

This invention relates to a wire stitching machine.

One of the objects of the present invention is to simplify and increase the efficiency of 5 the wire stitching machine by providing a construction which will simultaneously stitch a plurality of staples in spaced relation.

A further object of the invention is to provide a single driving mechanism and a single 10 head upon which is mounted an improved construction of a plurality of stitch forming and driving devices, which are operably driven by a common driving mechanism.

These and other objects are accomplished 15 by providing a construction and an arrangement by means of which a plurality of staple formers and drivers are connected together in such a manner that the mechanism ordinarily used to drive a single former and driver 20 are employed to drive a plurality of the same, and yet maintain them at a considerable distance apart.

Referring to the drawings—

Figure 1 is a front elevational view of my 25 improved stitching machine;

Fig. 2 is an enlarged fragmentary front elevational view showing the manner in which the two staple forming and driving mechanisms are connected together and operably 30 driven by a single driving mechanism;

Fig. 3 is an enlarged cross-sectional view taken on the lines 3—3 in Fig. 1;

Fig. 4 is a cross-sectional view taken on the lines 4—4 in Fig. 2;

Fig. 5 is a top plan view of the detailed 35 construction of my improved staple forming and driving mechanism showing the same removed from the machine;

Fig. 6 is an enlarged front elevational view 40 of the staple forming mechanism;

Fig. 7 is a top plan view of Fig. 6;

Fig. 8 is a side elevational view of Fig. 6;

Fig. 9 is a cross-sectional view taken on the 45 lines 9—9 of Fig. 6 showing the manner in which the two staple formers are secured together; and

Fig. 10 is a side elevational view of the staple driver.

The present invention is applied to wire 50 stitching machines of the general character well known in the art, and only that portion of the machine is shown in the drawings to sufficiently illustrate the present invention and its relative parts.

The whole stitching mechanism, which con-

stitutes the head, is supported on the horizontally disposed supporting frame or arm 15, which rotatably supports a shaft 16 in a horizontal bore 17. Secured to the forward end of the arm 15 is a vertically disposed plate 60 or head 18 upon which the operative parts of the stitcher are mounted. A reduced portion of the shaft 16, indicated at 19, extends past the plate 18, and has secured thereto by means of a key not shown a cam 20. Securely 65 mounted in any well known manner on a collar 21 formed integrally with the cam 20 is a spur gear 22, as clearly shown in Fig. 3. The lower portion of the plate 18 has secured thereto in any well known manner a block 23. 70 The block 23 is provided on the opposite sides thereof with vertically extending grooves or recesses 24 and 25 on its front side, through which the staple formers 26 and 27 are mounted for vertical sliding movement. The 75 forward or front side of the staple formers 26 and 27 are provided with vertically extending channels or grooves 28 and 29 respectively, which are adapted to reciprocally receive staple drivers 30 and 31. 80

My improved construction of spaced staple drivers 30 and 31 are operatively connected together by cross-bar 32, which has its outer ends connected by means of bolts 33 to the upper ends of the drivers 30 and 31 respectively, as clearly shown in Fig. 2. Extending downwardly from the center portion of the cross-bar 32 and formed integrally therewith is a guiding member 35, which is adapted for vertical reciprocatory movement in the groove 85 or recess 36 formed by two oppositely and vertically disposed guiding bars 36 secured to the block 23 by means of screws 23'.

From this construction it will be seen that the guiding member 35 of the cross-bar 32 90 positively insures the vertical reciprocation of the driving members, and eliminates the possibility of these members becoming cramped in their respective vertical grooves within which they operate. 100

The drivers 30 and 31 are driven by means of a pitman 37 having one end thereof connected at 38 to the cross-bar 32, and the other end connected eccentrically to the cam 20 at 39. The staple formers 26 and 27 are of the usual form, and are similarly connected together by cross-bar 40. The cross-bar 40 has downwardly extending therefrom and formed integrally therewith a guiding member 41, 105 which is adapted to vertically reciprocate in 110

a groove 42 formed in the front side of the block 23. Staple formers 26 and 27 are secured to the cross or T-bar 40 by means of screws 43. The staple formers are operatively 5 driven in their respective grooves or channels by means of a roller 44 pivotally secured on the rear side of the cross-bar 40, and adapted to engage a cam groove 45 formed in the cam 20.

10 Reciprocally mounted in the bores 46 of the block 23 adjacent each staple forming and driving mechanism are the usual anvils 47. The anvils 47 are pressed forwardly by compression springs 48, having one of their 15 ends seated in the bores 49 of the anvils 47, and the other ends thereof engaging the washers 50 secured to the rear side of the block 23. The anvils 47 are provided with the usual horizontal grooves 51 through 20 which the wires are fed and held during the time they are being formed into staples. Pivotally mounted forwardly of each of the anvils 51 are the usual staple supporters 52, which are normally pressed into the position 25 shown in Fig. 3 by pins 53 and compression springs 54 seated in the sockets 55 of the outer casing 56. Secured to the outer legs of the staple formers 26 and 27 are the usual cutting knives 57. Positioned adjacent the 30 anvils 47 and extending through the outer sides of the block 23 is the usual feed tubes 58 held in relatively fixed position by clamping bolts 59.

35 My improved double staple former and staple driver construction is provided with the wire feeding mechanism described and claimed in my previous application, Serial No. 660,763, filed September 4, 1923. This wire feeding mechanism comprises two oppositely disposed feeding rolls 60 and 61, which are operatively driven through a train of gears connected with the power shaft 16. The feeding rolls 60 and 61 are provided with the usual feeding cams 62 and 63 respectively. 40 The feeding roller 60 may be adjusted with respect to the feeding roll 61, so that the length of the wire fed may be varied when it is desired to vary the length of the staple. The feeding roller 60 is rotatably mounted 45 on a bracket 64 pivoted to the main frame of the machine, and the free end of the bracket is resiliently pressed by means of a spring 65 and thumb screws 66 in such a manner that the feed roll 60 yieldingly impinges the wire fed between the feeding cams 62 and 63 when the wire is fed to the staple forming and driving mechanism.

50 In the present machine, the usual straightening device 67 for straightening the wire as the same is fed into the feed rolls is provided, and also the usual checking device 68 is provided which prevents the withdrawal of the wire from the staple former and driving mechanism after the same has been fed.

55 In the construction of my improved dou-

ble stitching machine, it will, of course, be understood that I have provided two sets of feeding rollers on the opposite sides of the machine, and so positioned that each of these feeding mechanisms are driven from the common power shaft. 70

It will also be understood that the wire is fed from each of these wire feeding mechanisms into their respective staple forming and driving mechanism wherein the wire is 75 formed into staples and driven by the driver into the work. The wires are fed to these feeding mechanisms from spools 69, only one of which is shown, which are supported by an arm 70 formed integrally with the 80 plate 18.

In the operation of the above described device, it will, of course, be understood that each of the wires are fed from their respective spools through the wire straightening 85 device past the wire checking device, where it is engaged by the feed rollers and forced through the wire guide tube into the horizontal grooves 51 of the respective anvils 47, after which the staple formers 26 and 27 are 90 actuated in their downward movement to cut these wires by the knives 57. On a further downward movement of the staple formers the outer ends of the wire are bent by the legs of the former which engages the outer sides of the anvil, and forms the wire 95 into a staple. At the completion of the staple forming movement the staple drivers are operatively driven downwardly, forcing the anvils 47 into the block 23 against the compression of the spring 48 by contacting the beveled forward edge of each of the anvils. After the anvils have been withdrawn from the staples the drivers drive the staples into the work supported beneath the machine. 100 It, of course, being understood that the supporters 52 support the staples after the anvils are withdrawn, and continue to support the staples until they are driven into the work by the drivers. 105

110 From the above construction it will be seen that I have provided a very simple and efficient double staple forming and driving mechanism, and one in which the staples may be driven into the work and at the same time be spaced apart at a considerable distance.

115 It will also be understood that this same principle of construction may be employed with a greater number of staple forming and driving mechanisms operated by a single power shaft and cam mechanism, and yet retain the essential features of my invention. In other words, more than two staple formers and drivers could be mounted on a similar cross-bar and operated just as efficiently 120 as the two mechanisms here shown and described, but in such a construction of course it would be necessary to angle the feeding mechanism, and also the staple formers and driving mechanism, so that the wire could 125 130

be fed in an angle of substantially 45 degrees to the face of the cam. By this arrangement any number of staple formers and driving mechanisms may be operated on a single cross-bar.

It is, therefore, within the contemplation of my invention to cover all structures embodying this essential feature of construction.

10. What I claim as my invention and desire to secure by Letters Patent is:

1. A wire stitching machine comprising a frame, a drive shaft located centrally in said frame, wire feeding mechanisms located on the opposite sides of said shaft and operatively connected therewith, staple forming and driving mechanisms located on the opposite sides of said shaft, cross bars slidably mounted on said frame for connecting said forming and driving mechanisms, and means for connecting said bars to said shaft in a manner to actuate said forming and driving mechanisms in co-operation with their respective wire feeding mechanisms.

25. 2. A wire stitching machine comprising a frame, a drive shaft mounted thereon, a plurality of wire feeding mechanisms operatively driven by said drive shaft, a cam fixed to said shaft and a plurality of staple forming and driving mechanisms located on the opposite sides of said shaft, and operatively connected to said cam for operatively driving said staple forming and driving mechanisms.

3. A wire stitching machine comprising a frame, a drive shaft mounted thereon, a plurality of wire feeding mechanisms operatively driven by said drive shaft, a cam fixed to said drive shaft, a cross-bar connected with said cam having a plurality of wire staple formers secured thereto, a second cross-bar connected with said cam having a plurality of staple drivers secured thereto, and means for operatively driving all of said staple formers and drivers.

45. 4. A wire stitching machine comprising a frame, a driving shaft mounted thereon, a plurality of wire feeding mechanisms operatively driven by said drive shaft, a cam fixed to said drive shaft, a cross-bar connected with said cam having a plurality of wire staple formers secured thereto, a second cross-bar connected with said cam having a plurality of staple drivers secured thereto, said staple drivers mounted for reciprocatory movement in grooves formed in said staple formers, and means for operatively driving all of said staple formers and drivers.

5. A wire stitching machine comprising a frame, a drive shaft mounted thereon, a plurality of wire feeding mechanisms operatively driven by said drive shaft, a cam fixed to said drive shaft, a cross-bar mounted on said frame for vertical reciprocatory movement and operatively connected to said cam, a plurality of staple formers connected to

said cross-bar, a second cross-bar mounted on said frame for vertical reciprocatory movement and operatively connected to said cam, a plurality of staple drivers connected to said second cross-bar, and means for operatively driving all of said staple formers and drivers.

6. A wire stitching machine comprising a frame, a drive shaft mounted thereon, a plurality of wire feeding mechanisms operatively driven by said drive shaft, a cam fixed to said drive shaft, a cross-bar mounted on said frame for vertical reciprocatory movement and operatively connected to said cam, a plurality of staple formers connected to said cross-bar, a second cross-bar mounted on said frame for vertical reciprocatory movement and operatively connected to said cam, a plurality of staple drivers connected to said second cross-bar, a guiding member formed integrally with each of said cross-bars to insure vertical reciprocation of said bars, and means for operatively driving all of said staple formers and drivers.

7. A wire stitching machine comprising a frame, a stitcher head mounted on said frame, a drive shaft mounted in said frame and stitcher head, a plurality of wire feeding mechanisms mounted on said head at opposite sides of said shaft and operatively connected to said shaft in a manner to be driven thereby, a plurality of staple forming and driving mechanisms mounted on said head at opposite sides of said shaft and cooperating with said wire feeding mechanism, and means mounted in said head and operatively connected to said staple forming and driving mechanisms and to said shaft in a manner to cause said forming and driving mechanisms to be actuated by said shaft.

8. A wire stitching machine comprising a frame, a stitcher head mounted on said frame, a drive shaft mounted in said frame and stitcher head, a plurality of wire feeding mechanisms carried by said head and operatively driven by said drive shaft, a cam fixed to said shaft, a plurality of cross bars operatively connected to said cam in a manner to be reciprocated vertically thereby, and a plurality of staple forming and driving mechanisms connected to the respective cross bars at opposite sides of said shaft and operatively driven thereby.

9. A wire stitching machine comprising a supporting arm, a stitcher head secured thereto, a drive shaft mounted in said arm and head, a pair of wire feeding mechanisms positioned on said head at opposite sides of said shaft and operatively connected thereto in a manner to be driven thereby, a pair of staple forming and driving mechanisms slidably mounted on said head at opposite sides of said shaft and in the radial planes of said feeding mechanisms, a plurality of cross bars for connecting said staple forming and driving

mechanisms, and means for operatively connecting said bars to said shaft in a manner to actuate said staple forming and driving mechanism.

5 10. A wire stitching machine comprising a supporting arm, a stitcher head secured thereto, a drive shaft mounted in said arm and head, a pair of wire feeding mechanisms positioned on said head at opposite sides of said 10 shaft and operatively connected thereto in a manner to be driven thereby, staple formers slidably mounted on said head at opposite sides of said shaft and in the radial planes of said feeding mechanisms, staple drivers slidably mounted in said formers, a cross bar for 15 connecting said formers, a second cross bar for connecting said drivers, a cam member secured to said shaft, and means for operatively connecting said cross bars and member in a 20 manner to cause the reciprocation of said cross bars for actuating said staple formers and drivers.

11. A wire stitching machine comprising a supporting arm, a stitcher head secured there-

to, a drive shaft mounted in said arm and head, a pair of wire feeding mechanisms positioned on said head at opposite sides of said shaft and operatively connected thereto in a manner to be driven thereby, staple formers 25 slidably mounted on said head intermediate the vertical planes of said feeding mechanisms and said shaft and in the radial planes of said feeding mechanisms, staple drivers 30 slidably mounted in said formers, a cross bar for connecting said formers and having a central portion slidably mounted on said head, a second cross bar for connecting said drivers and having a central portion slidably mounted in a guideway formed on said head, a cam 35 member secured to said shaft, and means for operatively connecting said cross bars and member in a manner to cause the reciprocation of said cross bars for actuating said staple drivers.

In testimony whereof I have signed my 40 name to this specification.

ERNEST LESCHHORN.
